UNITED STATES PATENT OFFICE.

LOUIS A. KAMPELMAN, OF ST. LOUIS, MISSOURI.

PLAYING MECHANISM FOR STRINGED INSTRUMENTS.

No. 848,658.

Specification of Letters Patent.

Patented April 2, 1907.

Application filed March 9, 1906. Serial No. 305,094.

To all whom it may concern:

Be it known that I, LOUIS A. KAMPELMAN, of the city of St. Louis and State of Missouri, have invented certain new and useful Improvements in Playing Mechanism for Stringed Instruments, of which the following is a full, clear, and exact description.

My invention relates to a playing mechanism for stringed instruments; and the object 10 of my invention is to provide a mechanically-operated mechanism for striking and sounding the strings of musical instruments, such as zithers, harps, and pianos.

I attain the object above stated by certain mechanism which will be hereinafter more fully described, and pointed out in the claims and illustrated in the accompanying drawings, in which—

Figure 1 is a vertical section taken 20 through one end of a stringed instrument and showing one of the electrically-operated hammers which strikes the wires of the musical instrument. Fig. 2 is a vertical section taken on the line 2 of Fig. 1. Fig. 3 is a 25 detailed section showing the connection between the hammer and the armature carrying the same.

Referring by numerals to the accompanying drawings, 69 designates the base of a 30 stringed musical instrument, and 70 the strings thereon.

71 designates a transversely-extending bar at the end of the musical instrument, and fixed thereto immediately over each string 35 is a pair of magnet-coils 72, which are connected in the usual manner, and a suitable conductor 73 leads from the upper one of each coil to a suitable source of electrical supply. The lower one of each of the pairs 40 of coils is connected by a suitable conductor 74 to a transverse metallic rod 75, carried by the bar 71, immediately below the roll of magnet-coils 72. The cores 76 of the magnet-coils extend forwardly and are connected by 45 a transverse bar 77. Pivotaly connected to the center of each bar 77 is an armature 78, and secured to each armature adjacent its pivot-point is a retractile coil-spring 79, the rear end of which is secured to the bar 71. 50 Seated in each armature 78 is a forwardly-projecting rod 79^a, in the outer end of which is pivotally mounted a rod 80, the forward end of which carries a small hammer-head 81. The parts just described are so arranged as 55 that each hammer is positioned above a corresponding one of the instrument-strings 70

and strikes thereon when swung downwardly. A leaf-spring 82 is fixed on top of each arm 79^a, and the free end of said leaf-spring bears on top of the rear end of the rod 80, that is pivoted in said arm 79^a. These leaf-springs are for the purpose of maintaining the hammers in an elevated position after they have struck the wires.

The rod 75 is suitably connected by a conductor to the source of electrical supply to which the conductor 73 is connected.

The operation of my improved playing mechanism is as follows: When one of the magnets comprising the two coils 72 is energized by a current passing through the conductor 73, the armature 78 of said magnet is drawn into a vertical position, with its ends between the ends of the magnet-cores 76, and this motion brings the arm 79^a, carried by 75 said armature, and the rod 80, carried by said arm, downwardly, and this sudden motion of the armature causes the rod 80 to swing upon its pivot-point, overcoming the resistance offered by the leaf-spring 82, and 80 as a result the hammer 81 strikes upon the string 70, sounding same, and then the hammer, comprising the rod 80 and head 81, is instantly elevated or rebounds a short distance and is so held by the tension of the leaf-spring 82. When the current through the conductor 73 is broken, the coil-spring 79 will act to swing the armature 78 and parts carried thereby back to their normal positions. By providing two magnet-coils the 85 magnetic force is equally balanced, and when the circuit is interrupted the armature will at once return to its original position without noise. The rod 80, carrying the hammer-head 81, being pivotally connected to the 90 arm 79 and being normally held by the spring 82 forms means for imparting a quick blow on the instrument-strings, and the hammer is instantly elevated, so as to allow the strings to vibrate properly.

The entire apparatus is simple and inexpensive and may be applied to various forms of stringed instruments.

I claim—

1. In a playing mechanism for stringed instruments, a pivotally-mounted member arranged to swing vertically, means whereby said member is caused to swing upon its pivot-point, an arm projecting from the front side of said member, a second arm pivotally connected to the outer end of the first-mentioned arm, a hammer-head carried by the end of

the second-mentioned arm and a spring secured to the first arm and bearing upon the top of the rear end of the second arm, substantially as specified.

5 2. A musical instrument comprising horizontal strings, a series of magnet-coils positioned above the strings, the cores of which magnets are extended, an armature pivotally mounted between the extended cores, an 10 arm projecting from the front side of said armature, a second arm pivotally connected to the first-mentioned arm and a spring normally engaging the rear end of the second arm for maintaining it in an elevated position, substantially as specified.

15 3. A musical instrument comprising horizontal strings, a series of magnet-coils posi-

tioned above the strings, the cores of which magnets are extended, a spring-held armature pivotally mounted between the extended ends of each pair of cores, an arm carried by the lower end of each armature, a second arm pivotally connected to the first arm, a hammer carried by the second arm, and a spring engaging on the rear end of the second 20 arm for normally holding it elevated, substantially as specified.

In testimony whereof I have hereunto set my hand in the presence of two subscribing witnesses.

LOUIS A. KAMPELMAN.
